[57] CLAIM

The ornamental design for a novelty paddle, as shown.

DESCRIPTION

FIG. 1 is a right front perspective view of a novelty paddle, showing my new design;
FIG. 2 is a side elevational view, the other side elevational view being substantially a mirror image thereof;
FIG. 3 is an end elevational view taken from the right hand end of the design shown in FIG. 2;
FIG. 4 is an end elevational view taken from the left hand end of the design shown in FIG. 2;
FIG. 5 is a top plan view; and,
FIG. 6 is a bottom plan view.

FIG-1
